DESIGN FOR A BACK PLATE FOR WALL BRACKETS OR ARTICLES OF ANALOGOUS NATURE

Application filed March 28, 1931. Serial No. 39,215. Term of patent 7 years.

To all whom it may concern:

Be it known that I, ERNEST A. WALKER, a citizen of the United States of America, and a resident of Newark, county of Essex and State of New Jersey, have invented a new, original, and ornamental Design for a Back Plate for Wall Brackets or Articles of Analogous Nature of which the following is a specification, reference being had to the accompanying drawings, forming a part hereof.

In the drawings:

Figure 1 is a front elevational view of the back plate for wall brackets or articles of analogous nature; and

Figure 2 is a diagrammatic side elevational view of the same.

I claim:

The ornamental design for a back plate for wall brackets or articles of analogous nature substantially as shown.

ERNEST A. WALKER.
